DIODE RECTIFIER CIRCUIT

Loy E. Barton, Collingswood, N. J., assignor to
Radio Corporation of America, a corporation
of Delaware

Application January 31, 1935, Serial No. 4,243

1 Claim. (Cl. 250—27)

The present invention relates to diode rectifier circuits, particularly adapted for detecting high frequency modulated signals, and has for its object to provide an improved diode rectifier circuit 5 for supplying rectified signals directly to a balanced audio frequency output stage for radio receiving apparatus and the like.

It is a further object of the present invention to provide an improved radio receiving system 10 wherein signals of relatively high amplitude are supplied to a diode rectifier, whereby the rectifier output signals may be applied directly to a push-pull output or power amplifier stage without the intermediary of a driver stage.

15 It is a still further object of the present invention to provide an improved diode rectifier circuit for modulated signals and the like providing a push-pull or balanced output circuit from a single diode rectifier of the hot cathode 20 type.

20 It is also a further object of the present invention to provide an improved modulation indicator embodying a single diode rectifier device and a balanced output circuit therefor.

25 The invention will, however, be better understood from the following description when considered in connection with the accompanying drawing, and its scope will be pointed out in the appended claim.

30 In the drawing, Figure 1 is a schematic circuit diagram of a portion of a radio receiving system embodying the invention, and

Fig. 2 is a similar schematic circuit diagram of a modulation indicator embodying the invention.

35 Referring to Fig. 1, 5 is the output circuit from any suitable apparatus (not shown) for supplying modulated signals of high amplitude sufficient to operate an output amplifier stage 6 directly from a diode rectifier device 7 without the intermediary of a driver amplifier stage.

The rectifier device 7 is of the hot cathode type, comprising a filament 8 and an anode 9, the latter being connected to one side 10 of a 45 tuned circuit 11 suitably coupled to the output circuit 5 to receive signal energy therefrom.

The cathode or filament 8 is supplied with heating current from the secondary winding 12 of a heating transformer 13, the primary 14 of 50 which is adapted to be connected to a suitable source of alternating current supply. The secondary of the transformer is designed to have a low capacity to ground, that is, to the core or frame indicated at 15, and to the primary winding 14. The capacity is sufficiently

low to substantially isolate the cathode or filament 8 from ground by capacity coupling at the signal modulation frequency which is usually within the audio frequency range.

The cathode or filament 8 is provided with a 5 center tap connection through a center tap terminal 16 provided on the secondary winding 12, and, through this connection and a lead 17, the rectifier circuit is completed to the low potential terminal 18 of the input circuit 11 10 through a rectifier output resistor 19. With this arrangement, signals received in the rectifier input circuit 11 from the output circuit 5 flow from the high potential terminal 10 through the rectifier 7 and the cathode circuit 15 20 forming the connection with the secondary 12, and, from the cathode circuit, the rectified signals return by way of the center tap 16 through the lead 17 and the resistor 19 to the low potential terminal 18 of said input circuit. 20

The cathode circuit may be by-passed at radio frequencies by suitable by-pass condensers as indicated at 20a.

The rectified signals appear across the terminals 21 and 22 of the output re-

sistor 19. 25

Since the cathode 8 and its connection 17 with the terminal 22 of the output resistor 19 is isolated above ground at the modulation or audio frequency, the cathode end or terminal 22 of the output resistor 19, therefore, may vary 30 at the output frequency and 180° out of phase with the potential at the terminal 21 which is connected with the input circuit. A push-pull output circuit may, therefore, be connected with the terminals 21 and 22, and, for this purpose, 35 the center tap 23 is provided on the output resistor 19 and connected to ground as indicated at 24. High frequency currents in the rectifier circuit are by-passed around the resistor sections thus provided, by suitable by-pass condensers 25—25 connected in circuit between the grounded center tap 23 and the terminals 21 and 22. 40

It has been found that radio signals of sufficient amplitude may be provided to drive the 45 output stage 6 directly from the output terminals 21 and 22. For example, a signal potential of 100 volts or more may be provided between the terminals 21 and 22 with suitable input signal 50 amplitude in the circuit 11.

The output stage comprises a pair of balanced output electric discharge amplifier devices or tubes 26—26 having a balanced output circuit 27 connected through a suitable coupling trans- 55

former 28 to a loudspeaker or other signal output device 29.

By reason of the high signal voltage available across the terminals of the output resistor 19, the tubes 26 may be coupled thereto by simple impedance coupling means comprising coupling condensers 30 in output leads 31 and 32, extending from the terminals 21 and 22 to the control grids 33 of the tubes 26, and suitable bias supply resistors 34 connected between the grids 33 and a bias potential supply lead 35.

A balanced push-pull input circuit is, therefore, provided for the tubes 26 of the output amplifier stage in connection with the balanced output circuit of the single rectifier device 7. This arrangement results in the audio frequency amplification of the rectified signals without appreciable distortion and with comparatively simple amplifying means involving a minimum number 20 of circuit elements.

With this arrangement, the cathode end 22 of the output circuit floats at audio frequency in connection with one output grid while the anode or input end 21 floats at audio frequency in connection with the other grid of the balanced or push-pull output amplifier stage. This is permitted by causing the cathode or filament of a hot cathode diode rectifier to float at low capacity to ground and with a push-pull or balanced output resistor connected between the floating cathode connection and the high frequency input circuit.

Referring now to Fig. 2, a circuit similar to that of Fig. 1 is shown wherein the electric discharge device 40 is the rectifier or detector which receives modulated signals through an input circuit 41 and supplies rectified signals to the output terminals 42 and 43 of an output resistor 44, the center tap 45 of which is connected to ground as indicated at 46. High frequency by-pass condensers for each half of the resistor 44 to ground are indicated at 47.

In the present example, the rectifier device 40 is a hot cathode device of the equi-potential type comprising a cathode 48 and a heater element 49 therefor. The filament or heater 49 may be connected to any suitable source of heating current, for example, as shown in Fig. 1 and is sufficiently spaced from the cathode 48 to have a low capacity thereto, whereby the cathode 48 may float or be isolated from ground at audio or modulation frequencies. With this arrangement, the cathode is indirectly heated and the heating element may be connected to any suitable source (not shown), grounded or ungrounded, although the connection shown in Fig. 1 for the filament is at present preferred when an indirectly heated cathode is used. In case that the capacity between the cathode 48 and the heater 49 is sufficiently low, the heater cathode voltage is not important. The cathode is isolated from the heater by sufficient spacing to provide the desired low capacity.

The alternating current or signal output from the resistor 44 is applied to a pair of balanced amplifier devices 50 and 51 of the high-gain, high-impedance type. In the present example, pentodes are illustrated and each comprises a cathode 52, a cathode heater 53, a control grid 54, 70 a screen grid 55, suppressor grid 56, and an output anode 57.

The suppressor grids 56 are connected to the cathodes and the latter are connected together and to ground, as indicated at 58. The screen grids receive operating potential from a positive

supply lead 59 through a potential reducing resistor 60. Between the screen grids and the cathode there may be provided a filter condenser 61 for smoothing the supply voltage.

The output anodes 57 receive operating potential through neon lamps 62 and 63, one lamp being in the anode circuit of each tube.

The control grids 54 are connected each with one terminal of the resistor 44 through grid leads 64 and 65, the latter being connected directly to the rectifier output terminal 42, while the former is connected to the rectifier output terminal 43 through a suitable coupling condenser 66 which acts primarily as a stopping condenser to prevent the application of direct current potentials from the terminal 43 to the grids of the tubes.

In the present example, biasing potentials for the tubes 50 and 51 are taken from the resistor 44 as the result of signal flow and the tubes may, therefore, be termed "diode-biased". The potential applied to the grids is the drop in potential between the grounded mid-tap 45 and the terminals 42. This potential is applied directly to the grid 54 of the tube 51 through its connection with the lead 65 and the same potential is applied to the corresponding grid in the tube 50 through a direct current path provided by a leak resistor 67 connected between the lead 65 and the lead 64.

In each of the leads 64 and 65 there is provided a current limiting resistor 68 adjacent in circuit to the control grids 54.

In the circuits shown, it has been found that the resistance of each half of the resistors 44 may be approximately 25,000 ohms, the resistor 67 may be substantially 2 megohms and the limiting resistors 68 may each have a resistance of 200,000 ohms or more. The stopping condenser 66 may be of any suitable capacity having a relatively low impedance at audio frequency, such as .25 mfd., for example.

Signals from any suitable source, such as an antenna circuit 69, are applied to the input circuit 41 by suitable coupling therewith as indicated by the transformer 70, and the modulation is indicated by the lamps 62 and 63, the lamp 62 at full brilliancy indicating 100 percent up-modulation and the lamp 63 at full brilliancy indicated at 100 percent down-modulation.

The tubes 50 and 51 require low bias potentials for plate current cut-off, so that a normal signal potential of approximately 100 volts across each side of the resistor 44 may completely cut off the plate current. During modulation, at 100% 55 modulation peaks, the instantaneous value of the potential at the terminal 42 to ground is zero. Therefore, as the terminal 42 approaches near zero, the instantaneous bias on the tube 51 approaches zero, at which point plate current may 60 flow through the neon lamp 63, which indicates that the modulated signal has reached substantially zero instantaneous value.

It will be noted that at the instant the audio frequency signal at the terminal 43 reaches an upward value equal to the direct current or rectified signal potential at the terminal 42, the instantaneous voltage on the grid of tube 50 will be zero by virtue of the audio frequency coupling condenser 66 which effectively maintains the terminal 43 and the lead 64 at the same audio frequency potential. At the instant the bias potential of the tube 50 is essentially zero the neon lamp 62 will glow, indicating 100% upward modulation, if the resistor 44 is grounded at its center 70

point. An upward modulation indication may be derived by connecting the lead 64 through the condenser 66 for any percentage modulation, to a corresponding position along the resistor 44 in the section connected with the terminal 43, for percentages above 100%, as will be seen hereinafter.

For the indication of upward and downward modulation lower than 100% the audio frequency or modulation signal may be applied to the output circuit for connection with the balanced amplifier or to other output grid leads similar to leads 64 and 65, indicated at 70 and 71, each of which is connected with one of the output terminals of the output resistor 44 through suitable coupling condensers 72. The percentage modulation below 100% at which the tubes are to provide full glow of the neon lamps, is adjusted by adjusting the grid bias connection along the resistor 44 to the proper point, and is the percentage of the resistance section between the terminals 42 and 45, corresponding to the desired percentage modulation.

In the present example, the grid bias connection from each of the leads 70 and 71 is made through grid leak resistors 73 and 74, respectively, to a common connection 75 tapped as indicated at 76 with the mid-point of the section of the resistor 44 between the terminals 42 and 45 for 50% up and down modulation indication, the positive half wave of the carrier being modulated down toward zero amplitude and the negative half wave being modulated up toward zero amplitude. This is for the reason that the full signal output is available on the leads 70 and 71 with only half the signal bias. For other percentage modulation indication, the tap 76 may be adjusted along the resistor to other points.

For modulation indications over 100% upward, a reduced signal component may be derived from the resistor 44 as indicated by the tap connection 77 connected with an output lead 78 through a suitable coupling condenser 79. Full biasing potential is derived from the terminal 42 through a grid leak resistor 80. With this connection and the tap 77 at substantially the mid-point of the resistor section between the terminals 43 and 45, 200% upward modulation is required to cause full glow of an indicating device similar to that shown

in connection with the leads 64 and 65. It will, therefore, be seen that by suitably tapping the balanced output resistor 44, the ratio of signal voltage, that is modulation or audio frequency voltage, to the direct current component thereof, 5 may be adjusted to provide indication of any percentage modulation desired for full glow of the indicating means.

From the foregoing description it will be seen that the modulation indicator comprises a single 10 detector or rectifier device for supplying biasing potentials and rectified or demodulated signals to a pair of balanced amplifier devices, directly in connection with a balanced or push-pull output circuit in the detector circuit, and indicating 15 means in the amplifier output circuit.

Furthermore, while providing a balanced or push-pull signal output, the rectifier circuit at the same time, provides diode biasing potentials for both of the amplifier devices, the biasing 20 potentials varying in accordance with the signal strength.

It is obvious that the rectified signal component or direct current component of the signal flowing in the resistor 44 may be utilized to supply potentials for other purposes, as desired, without interfering with the operation as a balanced output means, through a suitable tap connection therewith as indicated at 81, for automatic volume 25 control supply, for example.

I claim as my invention:

In a radio receiving system, the combination with a single diode rectifier, of a balanced output amplifier comprising a pair of electric discharge amplifier devices having a balanced output circuit, and means providing a balanced input circuit therefor in connection with said rectifier, said last named means including an output resistor in circuit with the rectifier and having connection therewith whereby the terminal ends 40 thereof receive rectified signal voltages which are substantially 180° out of phase with each other, a mid-tap connection for said resistor, connections between said amplifier devices and said resistor on opposite sides of said mid-tap, and 45 means in said connections for supplying a biasing potential to said amplifier devices from one side of said mid-tap.

LOY E. BARTON.
